CLAIM

The ornamental design for a removable power and data storage module for a digital video camera, as shown and described.

DESCRIPTION

FIG. 1 is a perspective view of the power and data storage module.

FIG. 2 is a left side view of the module.

FIG. 3 is a right side view of the module.

FIG. 4 is a front view of the module.

FIG. 5 is a back view of the module; and,

FIG. 6 is top view of the module.
